UNITED STATES PATENT OFFICE.

CHARLES OPPENHEIM, OF CHICAGO, ILLINOIS, ASSIGNOR TO SEARS, ROEBUCK AND CO., OF CHICAGO, ILLINOIS, A CORPORATION OF NEW YORK.

DESIGN FOR A WATCH FOB.

Application filed November 1, 1923. Serial No. 28,726. Term of patent 14 years.

To all whom it may concern:

Be it known that I, CHARLES OPPENHEIM, a citizen of the United States, residing at Chicago, in the county of Cook and State of Illinois, have invented a new, original, and ornamental Design for Watch Fob, of which the following is a specification, reference being had to the accompanying drawing, forming a part thereof.

In the drawing, Figure 1 is a face view of a watch fob showing my new design; Figure 2 a bottom plan view of the same.

I claim:

The ornamental design for a watch fob as shown.

CHARLES OPPENHEIM.
